AUXILIARY HYDRAULIC DEVICE FOR PRESSES

Howard F. MacMillin, Mount Gilead, Ohio, assignor, by mesne assignments, to The Hydraulic Press Corporation, Inc., Wilmington, Del., a corporation of Delaware

Application August 16, 1934, Serial No. 740,148

10 Claims. (Cl. 100—70)

This invention relates to presses, and especially to those having their platens moved by non-hydraulic means.

One object of my invention is to provide a press having a platen moved by any convenient means whether hydraulic or non-hydraulic, and devices for generating fluid pressure operated by the motion of the platen, the fluid pressure thus generated being available for operating various hydraulically-actuated devices, and/or providing pressure control.

Another object is to provide, in a press operated by non-hydraulic mechanism, means for giving the press a hydraulic effect and hydraulic pressure control.

Another object is to provide a press having a mechanically-operated platen with hydraulic devices so connected that the motion of the platen causes these devices to generate fluid pressure, this being utilized to actuate an auxiliary hydraulic ram for exerting a hydraulic effect and giving a pressure control upon the work pieces, with the speed of a mechanical press.

Another object is to provide a press having a platen, movable by whatever means, with devices attached thereto for generating fluid pressure, together with an auxiliary hydraulic ram operated by this fluid pressure and adapted to give a pressure-controlled pressing effect: this auxiliary hydraulic ram being located in any desired place, such as in the platen or the bed of the press.

Another object is to provide a platen-operated hydraulic generating arrangement of the above-mentioned type, the auxiliary hydraulic ram and the hydraulic generator rams being of a double-acting nature so that the upward motion of the main platen retracts the auxiliary hydraulic ram.

In the drawings:

40 Figure 1 is a front elevation, partly in section, of a press embodying single-acting hydraulic generator rams and a single-acting auxiliary hydraulic ram;

45 Figure 2 is a side elevation of the press shown in Figure 1, partly in section, along the line 2—2 of Figure 1;

Figure 3 is a horizontal section along the line 3—3 of Figure 1;

50 Figure 4 is a front elevation, partly in section, of a portion of the press shown in Figure 1, but illustrating the use of double-acting generator rams in connection with a double-acting auxiliary hydraulic ram;

55 Figure 5 is a view similar to Figure 1, but with

the auxiliary pressing cylinder located in the bed of the press instead of in the platen;

Figure 6 is a diagrammatic view of a circuit whereby the pressing ram in Figure 4 may be lifted with the assistance of an external source 5 of pressure, such as air;

Figure 7 is a front elevation partly in section of a hydraulic circuit whereby the press may be given a two-stage effect through a booster action contributed by the generator pistons;

Figure 8 is a vertical section through a pilot-operated check valve employed in the present circuit.

Press with single-acting generator rams

15

Referring to the drawings in detail, Figure 1 shows a press having a base 1 joined by side members 2 to the top member 3, as by the strain rods 4 on which are threaded the nuts 5. Mounted on the base 1 is a work table or bed 6.

The side members 2 of the press are equipped with guide portions 7 adapted to receive a press platen 8 for longitudinal reciprocation. The keeping of the platen 8 in engagement with the guide portion 7 is assisted by the retaining plates 9 bolted to the side members 2 of the press.

The press platen 8 may be moved in any convenient manner, such as mechanically or hydraulically. For purposes of illustration, a gear-driven mechanical crank press is shown, but other types may be used without departing from the scope of my invention.

In the form of press shown, the platen 8 is provided with a cross shaft 10 journaled in bearings 11 on the upper portion of the platen 8.

Pivottally engaging the cross shaft 10 of the platen 8 is a connecting rod 12 having a lower bearing 13, surrounding the cross shaft 10. At its upper end, the connecting rod 12 is provided with an upper bearing 14, which surrounds the 40 crank portion 15 of the main drive shaft 16. The latter is journaled in bearings 17, mounted upon the side members 2 of the press.

The driving end of the main drive shaft 16 is provided with a gear 18 for this purpose. The gear 18 is connected by a clutch mechanism within the clutch housing 19 in such a manner that the gear 18 may be connected or disconnected from the main drive shaft 16, as desired. The clutch mechanism within the clutch housing 19 is actuated by the crank arm 20 mounted on the clutch shaft 21 and connected by the link 22 to the pedal rod 23. The latter is reciprocably supported in the bosses 24 attached to one of the side members 2, and is secured at its lower end 55

by the pivotal connection 25 to the foot pedal 26. By depressing or releasing the foot pedal 26, the gear 18 may be made to operatively engage the main drive shaft 16, or rotate loosely upon it. In this manner, the foot pedal 26 controls the press to provide for its executing working strokes or for its remaining idle, as may be desired.

The gear 18 is driven by a pinion 27, meshing therewith, and mounted upon the countershaft 10 28 journaled in the bearings 29 attached to the side members 2. The opposite end of the countershaft 28 from the pinion 27 bears a flywheel 30 and a pulley 31, whereby the press may be driven, as from an electric motor belted to this pulley. Accordingly, when the pulley 31 is thus rotated, the gear 18 also rotates loosely upon the main drive shaft 16. When the foot pedal 26 is depressed, the gear 18 drivingly engages the main shaft 16 and causes the crank portion 15 thereof 15 20 to move in an orbital path. This movement causes the connecting rod 12 to move up and down, carrying with it the platen 8.

The platen 8 in its lower portion is provided with a pair of generator cylinder bores 32, and an 25 auxiliary pressing cylinder bore 33. These cylinder bores are connected at their upper ends by the passages 34. Reciprocably mounted within the cylinder bores 32 are hydraulic generator rams 35, having their lower ends secured in sockets 36 in the base 1 (Figure 1). Leakage from the generator cylinders 32 is prevented by the provision of the packings 37, adapted to be compressed by glands 38.

Mounted for reciprocation in the auxiliary 35 35 pressing cylinder bore 33 is the auxiliary pressing ram 39, having an upper enlarged portion 40 and a lower reduced portion 41. Surrounding the reduced portion 41 is a coil spring 42, which is engaged by the enlarged head 40, thus providing 40 40 for retraction of the auxiliary pressing ram 39, when the platen 8 moves upward. Leakage from the cylinder bore 33 is prevented by the packing 43, engaged by the gland 44, which surrounds the reduced portion 41 of the auxiliary pressing ram 39.

To regulate the pressure developed in the operation of the press, as well as to replenish the fluid required, the generator plungers 35 are provided with longitudinal bores 85 which communicate by the pipe lines 86 with the pressure regulating valve 87. In the present embodiment (Figure 1) this valve is preferably of the type shown in the copending application of Ernst, Serial No. 669,493, now Patent No. 2,086,295, dated 50 50 July 6, 1937. Connected to the opposite side of the pressure regulating valve 87 by the line 88 is the check valve 89, which permits fluid to pass through itself toward the pressure regulating valve 87, but not in the opposite direction. The pipe lines 90 and 91 run from the remaining ports respectively of the pressure regulating valve 87 and check valve 89 to the "make-up" tank 92. The latter contains fluid under a low pressure, such as under a gravity head or low air pressure, 55 and supplies replenishment fluid to the generator cylinders 32, in the manner described below. A similar arrangement is used with the press shown in Figure 4.

In operation, when the foot pedal 26 is depressed and the platen 8 moves downwardly, fluid 70 within the generator cylinder bores 32 is placed under pressure by the stationary generator rams 35. This pressure fluid moves through the passages 34 into the auxiliary pressing cylinder 33, causing the auxiliary pressing ram 39 to move

downwardly. Thus the auxiliary pressing ram 39 is a positive-acting hydraulic plunger which performs actual pressing work by moving positively forward against the load, rather than a mere cushioning device which recedes under the load.

The pressure regulating valve 87 is so loaded as to discharge fluid from line 86 into line 90 during the working stroke, when a predetermined pressure is reached in the space above the auxiliary pressing ram head 40. On the upward or return stroke of the press, the check valve 89 permits this discharged fluid to be returned from the make-up tank 92 to the lines 86 by way of the lines 91 and 88 and the pressure regulating valve 15 15 87. A similar action occurs with the press shown in Figure 4.

As the auxiliary pressing ram 39 moves downwardly relative to the platen 8, it compresses the coil spring 42. When the platen 8 starts on its upward or return stroke, the generator cylinder bores 32 move upwardly relative to the stationary generator rams 35, thus releasing the pressure fluid from the auxiliary pressing cylinder 33. The energy stored in the compressed coil spring 42 25 then comes into play to retract the auxiliary pressing ram 39 by forcing it upwardly into its normal position of rest.

Press with double-acting pressure generating rams and auxiliary pressing rams 30

In Figure 4 a double-acting auxiliary pressing ram 45 is shown as being served by the double-acting pressure generating rams 46. The latter have enlarged piston heads 47 upon their upper 35 35 ends, and also have longitudinal bores 85 as in Figure 1. The pressure generating cylinder bores, the auxiliary pressing cylinder bore, the packing glands, and the remainder of the hydraulic circuit remain the same as in Figure 1, hence are 40 designated by the same numerals. The regulation and replenishment circuit is as in Figure 1.

The auxiliary pressing ram 45 (Figure 4) is provided with an enlarged head 48 and a reduced stem 49. The cylinder bores 32 and 33 are connected above the enlarged head 48 by the upper 45 45 passages 50; and below the enlarged head 48 by the lower passages 51. The latter also are located below the lowermost positions of the intensifier piston heads 47.

In the operation of the arrangement shown in Figure 4, as the platen 8 descends, the downwardly moving cylinder bores 32 cause the fluid to be placed under pressure by their engagement with the fixed pressure generating piston heads 55 55 47. This pressure fluid is forced through the upper passages 50 into the auxiliary pressing bore 33, causing the auxiliary pressing ram 45 to move downwardly and forwardly against the load, thus positively exerting its force upon the work piece. 60 When the platen 8 has completed its working stroke and starts its return stroke, the intensifier cylinder bores 32 move upwardly relative to the intensifier piston heads 47. The fluid above the enlarged head 48 of the auxiliary pressing ram 45 is thus drawn into the space above the pressure generating piston heads 47. At the same time, the fluid entrapped below the intensifier piston heads 47 is forced outward through the 65 lower passages 51 into the space beneath the enlarged head 48 of the auxiliary pressing ram 45. This causes the head 48 to rise, retracting the auxiliary pressing ram 45. The action of the pressure regulating valve 87 and the replenishment cir- 70 75

circuit is the same as previously described for Figure 1.

It will be further understood, from Figure 6, that the pressing plunger 49 of Figure 4 may be retracted by means of pressure applied to the replenishment fluid in the make-up tank 82, the plunger 46 being provided with the twin longitudinal bores 123 and 124 opening respectively into the space above and beneath the piston head 47. The pressure regulating valve 87 and the check valve 89 are similar in construction and operation to those in Figure 4. The fluid in the make-up tank 92 (Figure 6) is subjected, as by compressed air, to pressure high enough to balance the weight of the hydraulic pressing ram 49. It will be further understood that the auxiliary pressing ram may be placed in the press bed, as in Figure 5, instead of in the platen.

20 *Press with two-stage effect from external circuit and generator rams*

The press arranged according to the circuit shown in Figure 7 provides a two-stage effect. To accomplish this, the hydraulic pump 64 provides fluid to advance the pressing ram 49 rapidly until an intermediate pressure is reached, after which the hydraulic generating plunger 57 imparts such pressure to the fluid as to finish the operation at a higher pressure level.

30 To this end (Figure 7) the circuit is provided with a high pressure regulating valve 93 and a pilot-actuated pump unloading valve 94 of any suitable patterns, the types shown being those disclosed in the copending application of Ernst, Serial No. 669,493, now Patent No. 2,086,295, dated July 6, 1937. Between these is arranged a pilot-operated check valve 95 having a valve-opening plunger operated by fluid reaching it through the line 103 and normally permitting 40 fluid to go from valve 94 to valve 93, but forcibly opened under certain circumstances, hereinafter described, to permit fluid to go in the opposite direction. This check valve 95 may be of any conventional type, the type shown being described 45 in more detail below.

From the bore 59 of the generator piston 57, the line 96 leads to one side of the high pressure regulating valve 93, from the opposite side of which the line 97 leads to the check valve 95 and 50 the pilot line 98 leads to the pilot port of the pump unloading valve 94. From the opposite side of the check valve 95, the line 99 leads to a main chamber port of the pump unloading valve 94, to the opposite side of which is connected the line 55 60 from the pump 64. From the discharge ports of the valves 93 and 94 run the discharge lines 100 and 101 respectively, joining the common discharge line 102 which runs back to the supply tank 84.

60 To complete the circuit, the line 61 from the opposite side of the pump 64 is connected to the bore 59 of the plunger 58, whence a pilot branch 103 continues onward to the pilot port of the check valve 95.

65 The pipes 60 and 61 lead to the opposite ports 62 and 63, respectively, of the hydraulic pump 64. The latter is of a variable delivery type having a flow-control rod 65, which when moved in or out, varies the quantity and direction of the pressure fluid passing through the pipes 60 and 61. The flow-control rod 65 is connected by the link 66 to one arm of the bell-crank 61, the other arm thereof being connected by the link 68 to the cam push rod 69. This rod 69 is reciprocably mounted 70 in the bearings 70, attached to the upper frame 75

member 3, and has a yoke 11 at its lower end with a roller 72 which serves as a cam follower, engaging the cam 73 mounted upon the main drive shaft 16 of the press. The coil spring 74 urges the cam follower 72 downwardly against 5 the cam 73.

The pilot-operated check valve 95 shown in Figure 8 may be of any conventional type, the details of which form no part of the present invention. The check valve shown for purposes of 10 illustration consists of a casing 150 having threaded connections 151 and 152 to the pipes 99 and 97, respectively. The casing 150 is provided with a partition 153 with a valve seat 154 engaged by a valve member 155, mounted on the end of a valve rod 156. The latter passes through a bore 157 in the casing 150, into a valve-lifting chamber 158 having a cylinder bore 159. Secured to the opposite end of the rod 156 from the valve member 155 is a piston head 160, engaged by a 20 coil spring 161 of a pressure sufficient to overcome the action of gravity and tending to urge the valve member 155 lightly into engagement with the valve seat 154. Opening into the bore 159 is a port 162 leading to a longitudinal groove 25 163, which in turn, opens into a chamber 164 formed between the connecting casing 165 and the plug 166, closing the bore 159 and engaging the end of the coil spring 161. The casing connection 165 is threaded, as at 167, to a portion 30 of the casing 150 and has a passageway 168 leading therefrom into the pipe 103.

In the operation of the circuit shown in Figure 7, and during the working stroke, the line 60 from the pump 64 delivers fluid under pressure 35 through the valves 94, 95 and 93 and by way of the lines 99, 97 and 96 to and through the plunger 57 and the cylinder 53 to the space above the pressing plunger 49. The latter is forced downwardly onto the work piece until the pressure builds up to such an extent that it backs up in the pilot line 98 and operates the pilot plunger 40 of the pump unloading valve 94, thenceforth causing the line 60 from the pump 64 to discharge its contents into the discharge lines 101 45 and 102, thence into the tank 84. The further motion of the press platen 8 then causes the generating plunger 57 to continue to build up the pressure of the fluid and thereby to force the pressing plunger still further forward. When the 50 pressure of the fluid exceeds the load setting of the high pressure regulating valve 93 it actuates the latter, causing it to discharge the fluid from the line 96 into the discharge line 100 and thence by the line 102 into the tank 84 until the working stroke of the platen 8 has been completed. 55

The platen 8 then starts its return stroke, whereupon the flow from the pump 64 is reversed by the action of the cam 73. The fluid under pressure now passes through the line 61, the plunger 58 and the cylinder 52 into the space beneath the pressing plunger head 48, retracting the latter. Meanwhile the same fluid under pressure backs up in the pilot line 103 to the check 65 valve 95, entering the bore 159 (Figure 8) and urging the piston head 160 outwardly against the urge of the spring 161, thereby opening the check valve 95 by forcibly lifting the valve member 155 from its seat 154. This allows the fluid from the 70 space above the pressing plunger head 48 to pass through the plunger 57; the lines 96, 97 and 99; and the valves 93, 95 and 94 to the line 60, thence back to the pump 64. This cycle of operations 75 repeats itself as the platen 8 reaches its limits

of travel during its subsequent working and return strokes.

It will be further understood that the auxiliary pressing ram 39 might be placed in the bed 6 instead of in the platen 8, the intensifier rams then being carried by the platen. This arrangement is shown in Figure 5.

Having thus fully described my invention, what I claim as new and desire to secure by Letters 10 Patent is:

1. In combination in a press, a movable platen, a piston-and-cylinder assembly including a piston member and a cylinder member for generating fluid pressure operated by the motion of said 15 platen, one of said members being associated with said movable platen and the other member being mounted in a substantially stationary position relative thereto, and a second piston-and-cylinder assembly adapted to be operated by the fluid from 20 said press-operated means, said second piston-and-cylinder assembly being arranged to provide additional pressing movement to that of said platen.

2. In combination in a press, a movable platen, 25 a frame having a bed, means for generating fluid pressure operated by the motion of said platen, and a piston-and-cylinder assembly adapted to be operated by the fluid pressure from said platen-operated means, said piston-and-cylinder assembly being arranged between said platen and 30 said bed to provide additional pressing movement to the pressing movement of said platen.

3. In combination in a press, a movable platen, a frame, a cylinder bore within said platen, a 35 plunger reciprocable within said cylinder bore and secured to said frame, said plunger being arranged to oppose the motion of said platen and to compress the fluid within said bore, and a hydraulically-actuated device adapted to be operated by the fluid pressure generated by reason 40 of the relative motion between said cylinder bore and said plunger.

4. In combination in a press, a movable platen, 45 a frame, a pressure-generating piston-and-cylinder assembly including a piston member and a cylinder member operated by the motion of said platen, one of said members being associated with said movable platen and the other member being secured to said frame in a substantially stationary position relative to said platen-associated member and a second piston-and-cylinder assembly 50 mounted on said platen and adapted to be operated relatively to said platen by the fluid pressure from said platen-operated piston-and-cylinder assembly by reason of the relative motion between said platen and said frame.

5. In combination in a press, a movable platen, 60 a frame, a pressure-generating piston-and-cylinder assembly operated by the motion of said platen, the cylinder of said assembly being associated with said movable platen and the piston thereof being substantially immovably secured to said frame and a second piston-and-cylinder assembly 65 adapted to be operated by the fluid pressure from said platen-operated piston-and-cylinder assembly by reason of the relative motion between said platen and said frame, said second piston-and-cylinder assembly being arranged to provide additional pressing movement to the pressing movement of said platen.

6. In combination in a press, a movable platen, 70 a frame, a pressure-generating piston-and-cylinder assembly including a piston member and a cylinder member operated by the motion of said

platen, one of said members being associated with said movable platen and the other member being secured to said frame in a substantially stationary position relative to said platen-associated member, a second piston-and-cylinder assembly 5 adapted to be operated by the fluid pressure from said pressure-generating piston-and-cylinder assembly by reason of the relative motion between said platen and said frame, said second piston-and-cylinder assembly being arranged to provide additional pressing movement to the pressing movement of said platen, an external source of fluid connected to replenish the fluid in said assemblies, and pressure-responsive means adapted to relieve the fluid pressure in said assemblies 10 when it exceeds a predetermined pressure.

7. In combination in a press, a movable platen, a frame, a pressure-generating piston-and-cylinder assembly including a piston member and a cylinder member operated by the motion of said 20 platen, one of said members being associated with said movable platen and the other member being secured to said frame in a substantially stationary position relative to said platen-associated member, a second piston-and-cylinder assembly 25 adapted to be operated by the fluid pressure from said pressure-generating piston-and-cylinder assembly by reason of the relative motion between said platen and said frame, said second piston-and-cylinder assembly being arranged to provide additional pressing movement to the pressing movement of said platen, an external source of fluid connected to replenish the fluid in said assemblies, pressure-responsive means connected to 30 said source and adapted to discharge the excessive fluid pressure from said assemblies into said source when it exceeds a predetermined pressure, and means enabling the flow of liquid in one direction only between said assemblies and said source.

8. In combination in a press, a movable platen, a double-acting pressure-generating piston-and-cylinder assembly operated by the motion of said platen, and a second double-acting piston-and-cylinder assembly adapted to be operated by fluid pressure from said pressure-generating assembly. 40

9. In combination in a press, a movable platen, a double-acting pressure-generating piston-and-cylinder assembly operated by the motion of said platen, said assembly including a piston member and a cylinder member, one of said members being associated with said movable platen and the other member being mounted in a substantially stationary position relative thereto, and a second double-acting piston-and-cylinder assembly 50 associated with said movable platen and adapted to be operated by fluid pressure from said pressure-generating assembly.

10. In combination in a press, a frame, a movable platen movably mounted on said frame, a pressure-generating piston-and-cylinder assembly 60 connected between said platen and said frame and adapted to be operated by the motion of said platen, a second piston-and-cylinder assembly adapted to be operated by fluid pressure from said pressure-generating piston-and-cylinder assembly 65 by reason of the relative motion between said platen and said frame, and means to retract the piston of said second piston-and-cylinder assembly during the return stroke of said platen, said 70 retracting means comprising a source of pneumatic pressure operatively connected to said piston of said second piston-and-cylinder assembly.

HOWARD F. MACMILLIN.
